UNITED STATES PATENT OFFICE.

CHARLES T. HATCH, JR., OF ALBION, MICHIGAN, ASSIGNOR BY MESNE ASSIGNMENTS, TO UNION STEEL PRODUCTS COMPANY, OF ALBION, MICHIGAN, A CORPORATION OF MICHIGAN.

CONVEYER.

Application filed November 3, 1924. Serial No. 747,614.

This invention relates to improvements in conveyers.

The main object of this invention is to provide an improved conveyer well adapted for handling loaves of bread.

A further object is to provide an improved conveyer for loading or charging a series of carriers of a bread cooling conveyer such as shown in U. S. Letters Patent to Towne, No. 10 1,428,721, dated September 12, 1922.

Objects pertaining to details and economies of construction and operation of my invention will definitely appear from the detailed description to follow.

15 I accomplish the objects of my invention by the devices and means described in the following specification. The invention is clearly defined and pointed out in the claims.

A structure embodying the features of 20 my invention is clearly illustrated in the accompanying drawing forming a part of this application, in which:

Fig. I is a fragmentary elevation of a structure embodying the features of my invention partially in section on a line corresponding to line 1—1 of Fig. III.

Fig. II is a fragmentary elevation looking from the left of Fig. I, the supply and discharge conveyers being omitted.

30 Fig. III is a detail vertical section on a line corresponding to line 3—3 of Fig. I.

Fig. IV is a fragmentary plan view showing the relation of certain of the conveyer parts.

35 Fig. V is a fragmentary plan view of the driving connections for various parts.

Fig. VI is a fragmentary elevation partially in section on a line corresponding to line 6—6 of Fig. V.

40 In the drawing the sectional views are taken looking in the direction of the little arrows at the ends of the section lines and similar numerals of reference indicate similar parts throughout the several views.

45 Referring to the drawing, 1 represents a supply conveyer by means of which the loaves of bread or other articles are supplied to the machine, and 2 the discharge conveyer by means of which the cooled articles are 50 carried from the machine and delivered at any suitable point. These conveyers are conventionally shown.

I provide a cooling conveyer which is substantially that of Letters Patent No.

1,428,721 above referred to, and which consists of a plurality of carriers 3 carried by sprocket chains 4 on the sprockets 5. These carriers 3 are controlled by the conveyer ways 6 and 7 which have switch means therein for reversing and discharging the carriers, the switch means 8 of the lower ways delivering upon the discharge conveyer 2.

As the details of the cooling conveyer form no part of my present invention, the same are not described further herein.

However, I provide the discharge conveyer 2 with a guard 9 pivoted at 10 and yieldingly supported by springs 12 so that the loaves are prevented from falling from the conveyer 2 as the carriers discharge thereto, as indicated by dotted lines at 13. This guard, being yieldingly supported, swings out of the way as the carriers reverse to discharge the loaves, and automatically returns to erected position, as shown in 75 Fig. III.

The loaves are delivered to the feed conveyer 14 by the supply conveyer 1, a bridge 15 being disposed between the ends of these conveyers. The carrier 14 is supported by the pulleys 17 and 18, the upper reach of this conveyer 14 being supported by the table-like way 19 over which the belt travels so that the belt does not sag under a load. The lower reach of the belt is supported 85 and guided by the pulleys 20, 21 and by the belt tightener pulley 22.

The loaves are carried along upon the feed conveyer 14 and supported thereby until discharged therefrom by means of the load discharge conveyer consisting of the conveyer chains 23 on sprockets 24 and 25. The conveyer chains 23 carry the sweeps or flights 26 adapted to sweep across the feed conveyer 14, pushing the loaves therefrom on to the chute 27 down which they slide to the carriers 3.

The loading conveyer is driven with a step by step movement and its movement is timed so that the loaves are carried between a pair of its flights as shown in Fig. III, while the loading conveyer is at rest, the flights constituting sides for the feed conveyer. This step by step movement in the embodiment illustrated is secured by a 100 driving connection consisting of the motor 28 having driving connections, the details of which are not illustrated, to the shaft 29.

This shaft 29 is provided with a pinion 30 meshing with a gear 31 on the shaft 32. The shaft 32 has a crank 33 provided with a wrist pin 34 engaging a slot 35 in the connecting rod 36, thus providing a lost motion connection for the crank to the connecting rod. The other end of the connecting rod is connected to a rocker arm 37 on the shaft 38, the rocker arm carrying a pawl 39 meshing with the ratchet 40.

The ratchet 40 is connected to the shaft 41 which is in turn connected to the shaft 25' by means of the sprocket chain 42 and suitable sprockets on the shafts 25' and 41, so that a single complete rotation of the gear 31 will actuate the loading conveyer one step, allowing it to remain stationary for a considerable time so that a succeeding load may be positioned by means of the feed belt.

This train of gears comprises the gear 43 upon the shaft 38, a pinion 44 upon the shaft 41 and gears 45 and 46 coacting with the gears 44 and 43, respectively, the gears 45 and 46 being supported by a shaft 47.

The feed conveyer 14 is also driven from the motor 28, the shaft 29 being provided with a sprocket 48 for the sprocket chain 49 which engages the sprocket wheel 50 on the shaft 51 having a beveled gear 52 meshing with the coacting beveled gear 53 on the shaft 54 of the pulley 18 of the feed conveyer 14.

To support the feed conveyer 14 against lateral movement as the loaves are swept therefrom, the belt is provided with a series of hooks 55 which engage the rear edge of the conveyer way 19. To prevent wedging or jamming of the loaves against the ends of the flights 26 while the same are sweeping cross the feed conveyer 14, I provide a gate or guard 56 which is pivoted at 57 so as to be engaged by the flight in operative position and swung across the feed conveyer as shown by dotted lines in Fig. IV.

Before the feed conveyer comes to rest this gate is released and swings back to its initial position shown in Figs. II and IV. A spring 58 is provided for yieldingly holding this guard in its retracted position.

With this arrangement the bread may be continuously delivered by the supply conveyer which is carried forward to loading position by the feed conveyer and discharged therefrom on to the carrier 3 by the loading conveyer, from which the bread is delivered to the discharge conveyer 2, thereby minimizing the handling of the bread from the ovens to the wrapping machines, or as may be desired.

I have illustrated and described my improvements as I have embodied them in a machine for cooling bread, although certain features are desirable and readily adapted for use in other relations. I have not at-

tempted to illustrate or describe such uses as I believe the disclosure made will enable the adaptation of my improvements as may be desired.

Having thus described my invention what I claim as new and desire to secure by Letters Patent is:

1. In a structure of the class described, the combination of a supply conveyer, a discharge conveyer, a cooling conveyer delivering to said discharge conveyer, a feed conveyer to which said supply conveyer delivers comprising a belt, a supporting way for the upper reach of said belt, a delivery conveyer comprising sprocket chains supported transversely above said feed conveyer, flights mounted on said sprocket chains to sweep transversely across said feed conveyer and adapted when at rest to constitute side members therefor, means for driving said delivery conveyer with a step by step movement, a chute disposed at the side of said feed conveyer to receive the loaves delivered therefrom and deliver the same to said cooling conveyer, and a guard pivotally mounted at the front end of said feed conveyer to be successively engaged by the flights of said delivery conveyer to be swung thereby to operative position across the feed conveyer, said guard when released by the flights being adapted to return to its initial position longitudinally of said feed conveyer.

2. In a structure of the class described, the combination of a supply conveyer, a discharge conveyer, a cooling conveyer delivering to said discharge conveyer, a feed conveyer to which said supply conveyer delivers comprising a belt, a supporting way for the upper reach of said belt, a delivery conveyer comprising sprocket chains supported transversely above said feed conveyer, flights mounted on said sprocket chains to sweep transversely across said feed conveyer, means for driving said delivery conveyer with a step by step movement, and a chute disposed at the side of said feed conveyer to receive the loaves delivered therefrom and deliver the same to said cooling conveyer.

3. In a structure of the class described, the combination of a cooling conveyer, a feed conveyer comprising a belt, a supporting way for the upper reach of said belt, a delivery conveyer comprising sprocket chains supported transversely above said feed conveyer, flights mounted on said sprocket chains to sweep transversely across said feed conveyer and adapted when at rest to constitute side members therefor, means for driving said delivery conveyer with a step by step movement, a chute disposed at the side of said feed conveyer to receive the loaves delivered therefrom and deliver the same to said cooling conveyer, and a guard

pivottally mounted at the front end of said feed conveyer to be successively engaged by the flights of said delivery conveyer, said guard when released by the flights being adapted to return to its initial position longitudinally of said feed conveyer.

4. In a structure of the class described, the combination of a supply conveyer, a discharge conveyer, a cooling conveyer delivering to said discharge conveyer, a feed conveyer to which said supply conveyer delivers comprising a belt, a supporting way for the upper reach of said belt, a delivery conveyer comprising sprocket chains supported transversely above said feed conveyer, flights mounted on said sprocket chains to sweep transversely across said feed conveyer and adapted when at rest to constitute side members therefor, means for driving said delivery conveyer with a step by step movement, and a guard pivotally mounted at the front end of said feed conveyer to be successively engaged by the flights of said delivery conveyer to be swung

thereby to operative position across the feed conveyer, said guard when released by the flights being adapted to return to its initial position longitudinally of said feed conveyer.

5. In a structure of the class described, the combination of a belt feed conveyer, a delivery conveyer comprising flights mounted to sweep transversely across said feed conveyer and adapted when at rest to constitute side members therefor, means for driving said delivery conveyer with a step by step movement, and a guard pivotally mounted at the front end of said feed conveyer to be successively engaged by the flights of said delivery conveyer to be swung thereby to operative position across the feed conveyer, said guard when released by the flights being adapted to return to its initial position longitudinally of said feed conveyer.

In witness whereof I have hereunto set my hand.

CHARLES T. HATCH, JR.
